ATTORNEYS

UNITED STATES PATENT OFFICE

EUGENE HENRY, OF DETROIT, MICHIGAN

DESIGN FOR AN AUTOMOBILE EMBLEM PLATE

Application filed July 29, 1929. Serial No. 32,234. Term of patent 3½ years.

To all whom it may concern:

Be it known that I, EUGENE HENRY, a citizen of the United States, residing at 4547 Seyburn Avenue, city of Detroit, in the county of Wayne and State of Michigan, have invented a new, original, and ornamental Design for an Automobile Emblem Plate, of which the following is a specification, reference being had to the accompanying drawing, forming a part thereof.

I claim:

The ornamental design for the automobile emblem plate as shown.

EUGENE HENRY.
